UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

MOTOR ROTATION FOR ROCK DRILLS.

Application filed May 5, 1922. Serial No. 558,777.

To all whom it may concern:

Be it known that I, FRED M. SLATER, a citizen of the United States, and a resident of Easton, in the county of Northampton and State of Pennsylvania, have invented a certain Motor Rotation for Rock Drills, of which the following is a specification accompanied by drawings.

This invention relates to fluid actuated rock drills of the hammer type, having an independent motor for rotating the drill steel, but relates more particularly to a fluid actuated rotation motor having a casing adapted to be sleeved over a portion of the drill cylinder at the back end of the machine.

The objects of the invention are to simplify, strengthen and cheapen a motor construction of the type referred to, and also enable the parts to be readily assembled and disassembled.

To these and other ends, which will hereinafter appear, the invention consists of the features of construction and combinations of elements substantially as described and claimed in this specification and shown in the accompanying drawings, in which—

Figure 1 is a side elevation in longitudinal section of so much of a rock drill as will serve to illustrate the invention, the back end section being taken on the line 1—1 of Figure 2 or 4 looking in the direction of the arrows.

Figure 2 is a transverse sectional view on the line 2—2 of Figure 1 looking in the direction of the arrows.

Figure 3 is a perspective view of the motor casing and

Figure 4 is a perspective view of the cylinder back extension.

Referring to the drawings, the cylinder A in which the piston B reciprocates, is provided with the front head C and front head parts, into which the drill steel D extends in position to receive the impact blows of the piston.

A cylinder back extension E, forming a prolongation of the cylinder bore, is provided with a portion F extending into the cylinder, and is also formed with a flange G, and a rearwardly extending reduced portion H.

The drill steel D is adapted to be rotated by an independent rotation motor, preferably a gear motor of the fluid actuated type,

and in accordance with this invention, the motor casing J is open at front and back as indicated particularly in Figure 3, and is provided with a chamber K for the motor, and a sleeve portion L adapted to be sleeved over the reduced portion H of the cylinder back extension E. By means of such construction, the faced flange G of the cylinder back extension forms the front head of the motor casing. A back head O, fitted to the motor casing, as indicated in Figure 1, forms a common head for both the bore of the cylinder and the motor chamber K in the motor casing J. The parts of the machine are suitably held together by the usual side bolts P.

The motor comprises the rotary gears Q and R suitably mounted on roller bearings S on the studs T held in the back head O as by means of the tap screws U. One gear is 75 suitably connected by the shaft V to impart rotation to the drill steel and in this instance, the forward end of the shaft V is provided with the roller-bearing W and the pinion X meshing with the gear Y, which is 80 connected to the gear Z, meshing with the gear a on the rotating chuck b into which the drill steel D extends. The chuck b is suitably clutched to a chuck key c.

The supply of motive fluid to the machine is controlled by the throttle d having the handle e and the motive fluid passes to the drill cylinder through the passage f and to the motor casing through the passage g.

Motive fluid exhausts from the motor casing through the exhaust port h into the chamber j in the cylinder surrounding the driving shaft V and passes to atmosphere through the ports k.

I claim:

1. An independently rotated fluid actuated rock drill of the hammer type, comprising a cylinder and reciprocating piston, a cylinder back extension extending into the cylinder and having a flange and a rearwardly extending reduced portion, a motor casing sleeved over the reduced portion of said back cylinder extension and a common back head for both the cylinder bore and the motor casing.

2. An independently rotated fluid actuated rock drill of the hammer type, comprising a cylinder and reciprocating piston, a cylinder back extension extending into the cylinder and having a flange and a rear-

wardly extending reduced portion forming a prolongation of the cylinder bore, a motor casing open at front and back and having a chamber for the motor and a sleeve portion adapted to be sleeved over the said reduced portion of the cylinder back extension, and a common back head for both the cylinder bore and the motor casing.

3. An independently rotated fluid actuated rock drill of the hammer type comprising a cylinder and reciprocating piston, a cylinder back extension extending into the cylinder and having a flange and a rearwardly extending reduced portion forming

a prolongation of the cylinder bore, a motor casing open at front and back and having a chamber for the motor and a sleeve portion adapted to be sleeved over the said reduced portion of the cylinder back extension, whereby the said flange forms the front head of the motor casing, and a back head fitted to the motor casing and forming a common head for both the bore of the cylinder and the motor chamber in the said motor casing.

In testimony whereof I have signed this 25 specification.

FRED M. SLATER.
